MAGAZINE FOR WRITING INSTRUMENTS

Filed Oct. 3, 1925

Fig. 5. Fig. 6. Fig. 7
Inventor,

Maurice Alland,
by J. Stuart Freeman,
Attorney.

UNITED STATES PATENT OFFICE.

MAURICE ALLAND, OF ATLANTIC CITY, NEW JERSEY.

MAGAZINE FOR WRITING INSTRUMENTS.

Application filed October 3, 1925. Serial No. 60,222.

The object of the invention is to provide improvements in writing instruments, and particularly in that type which combines both a fountain-pen and a magazine pencil 5 in the same structure.

Another object is more particularly to provide in such an instrument an improved storage system within a specially constructed cap, and so arranged that the interior compartments of the storage system are accessible at all times, irrespective of whether the cap is in position as a cover for the pen or the pencil end of the instrument.

A further object is to provide an improved storage or magazine cap for a writing instrument wherein, not only several different colors of leads may be kept for the pencil, but soluble ink-pellets of two or more colors may be stored and are at all times ready for use in a pen adapted to make any color of ink, as the water or other solvent from within the reservoir passes over a soluble ink-pellet, as for instance a pen of the type described in co-pending application Serial No. 25 36,104.

Still another object is to provide a cap formed of a tube in which is positioned a second tube, spaced away from the first for a considerable extent to form a cylindrical space for the storage of leads, the second tube being provided with a partition to form the bottom of a space in which may be stored soluble ink-pellets, and a closure which when in normal position incloses the interior of both tubes and consequently the two mentioned storage chambers.

And a still further object is to provide in such a construction a cup having a flange or other means to prevent it from entering the inner tube more than a predetermined distance and in spaced relation with the said partition, whereby in addition to the cylindrical space for pencil leads, there is provided a space for ink-pellets of one color within the inner tube, between its partition and the bottom of the cup, and a second space for ink-pellets of a different color within the cup itself, the free end of the inner tube preferably extending beyond the outer tube and being threaded to receive

the closure, which when in normal position incloses said storage spaces, retains said cup in fixed position, and operatively supports an ink-eraser of any suitable material.

With these and other objects in mind, the invention comprises further details of construction and operation, fully brought out in the following description, when read in conjunction with the accompanying drawings, in which Fig. 1 is a plan view of a writing instrument comprising both a magazine pencil and a multi-color fountain-pen; Fig. 2 is a similar view of the improved storage cap for reserve leads and ink-pellets; Fig. 3 is a longitudinal diametrical section taken thru the magazine cap with its parts in assembled relations; Fig. 4 is a similar view of the several parts of the cap in spaced relation; Fig. 5 is a bottom plan view of the cap; Fig. 6 is a top plan view of the magazine cup; and Fig. 7 is a bottom plan view of the closure member of the said magazine cap.

Referring to the drawings, the writing instrument shown in Fig. 1 has a central body portion 1 containing a reservoir for a suitable solvent for the soluble ink-pellets which are supported by the dual holder 2 in the feed-member 3 adjacent to the pen-point or nib 4, said body portion being provided with threads 5 for engaging corresponding threads 6 within the improved cap hereinafter described. The opposite end of the instrument provides a magazine pencil 7 from which is adapted to extend the exposed end of a lead 8.

The improved cap for the instrument comprises a tube 9, having a bore 10, provided at one end with the threads 6, beyond which is an enlarged portion 11 of the bore, adapted to receive and partially cover one end of the reservoir, or the central body portion 1 of the instrument. The oppositely positioned major portion of the bore 10 is also enlarged at 12, to form a cylindrical space outside of a second tubular member 13, adapted to contain a reserve supply of replacement leads 8 for the pencil 7.

The tube 13 is also provided with a transversely extending partition 14, beyond which

- is a compartment 15 in which are adapted to be positioned ink-pellets (not shown) of a given color, said compartment being closed normally by the inner end or bottom 16 of 5 a cup having side walls 17, slidably into the otherwise open end of said tube, and limited in its inward movement by a radial flange 18 having a circumferential finger-nail groove 19. This cup is adapted to contain 10 ink-pellets of a different color than those in the compartment 15, and in order to expose the interior of said compartment the flange 18 of the cup is engaged by one's finger-nails within the groove 19 whereby the cup is 15 readily removed.

It will be noticed that the inner tube 13 extends beyond the adjacent end of the outer tube 9 and is provided with threads 20 for engagement with threads 21 of a hollow 20 closure member 22, the lower enlarged end of which constitutes a flange 23, which normally bears against the upper end of the tube 13, while the upper end of said closure terminates in a radially inwardly extending 25 flange 24, beneath which is secured the flanged portion 25 of an abrasive member 26, comprising an eraser of any suitable material.

In the operation of this device, the space 30 12 is intended to be filled with replacement leads as shown in Fig. 3, while the compartment 15 contains ink-pellets of a given color, and the cup 16—19 contains ink-pellets of any other desired color. The closure 35 member when in operative position, also as shown in Fig. 3, serves to retain the cup in fixed position, to cover the otherwise open end of the lead compartment 12, to close the otherwise open end of the cup, which latter effects a closure of the compartment, and finally to secure the eraser member in fixed 40 relation with the said closure.

Having thus described my invention, what I claim and desire to protect by Letters Patent of the United States is:—

1. A writing instrument, comprising a cap formed of a pair of radially spaced concentric members, providing a cylindrical space between them for the storage of leads, 50 a removable closure carried by said members, and a replaceable abrasive member secured in said closure by, and when said closure is in normal cooperation with, said first members.

2. A writing instrument, comprising a pair of concentric tubular members, providing a cylindrical space between them for the storage of leads, and a member removably secured to one and cooperating with the 60 other of said first members when in normal position to form a closure for said space.

3. A cap for writing instruments, comprising a pair of concentric tubular members, secured together in fixed relation and being spaced apart throughout a portion of

their longitudinal extent to provide a cylindrical space for the storage of leads, the inner member having a transversely extending wall defining a centrally positioned space for the storage of ink-pellets, and a member removably secured to one and cooperating with the other of said first members to normally form a closure for said storage spaces. 70

4. A writing instrument, comprising a cap formed of a pair of concentric tubular members, secured together in fixed relation and being spaced apart throughout a portion of their longitudinal extent to provide a cylindrical space for the storage of leads, 75 the inner member having a transverse wall defining a centrally positioned space for the storage of ink-pellets, a removable cup-shaped member normally extending into and occupying a portion of said space and also 80 adapted to contain ink-pellets, and a member removably secured to one of said tubular members to normally form a closure for said storage spaces and cooperating with, and thereby operative to retain, said cup-shaped 85 member in fixed position.

5. A writing instrument, comprising a cap formed of a pair of concentric tubular members, secured together in fixed relation and being spaced apart throughout a portion of 90 their longitudinal extent to provide a cylindrical space for the storage of leads, the inner member having a wall defining a centrally positioned space for the storage of ink-pellets, a removable cup-shaped member 95 normally extending into and occupying a portion of said space and also adapted to contain ink-pellets the inner extending freely beyond the outer of said tubular members and being threaded, and a member removably secured to the threaded portion of 100 said inner and normally cooperating with the outer of said tubular members and forming a closure for said storage spaces, and operative to positively retain said cup-shaped member in fixed operative position. 105

6. A cap for writing instruments, comprising a tubular member forming a compartment and having a threaded end portion, a cup-shaped member normally extending partially into said compartment and provided with a flange to limit the inward movement of said last-named member, said flange being provided with a groove for manually engaging the flange to remove said 115 cup-shaped member from said compartment, and a closure for said tubular member operative to retain said cup-shaped member in operative position.

7. A cap for writing instruments, comprising concentric radially spaced cylindrical walls providing a storage space therebetween, a wall defining the inward limit of the interior of the inner of said walls, the inner wall extending freely beyond the outer 120 125

wall, a removable cup-shaped member within the interior of the inner wall and having a radial flange to limit its inward movement, a closure member having an aperture surrounded by a flange, and a protruding abrasive member removably secured in said closure by said last-named flange, said closure being removably threaded upon the free end

of the said inner wall, said closure bearing against the outer wall when in normal position, and causing said abrasive member to bear against and to normally prevent relative movement of said cup-shaped member. 10

In testimony whereof I have affixed my signature.

MAURICE ALLAND.
